UNITED STATES PATENT OFFICE.

JOSEPH W. NETHERY, OF INDIANAPOLIS, INDIANA, ASSIGNOR TO THE NETHERY HYDRAULIC VALVE COMPANY, OF INDIANAPOLIS, INDIANA, A CORPORATION OF NEW JERSEY.

VALVE.

SPECIFICATION forming part of Letters Patent No. 752,176, dated February 16, 1904.

Application filed October 11, 1902. Serial No. 126,831. (No model.)

To all whom it may concern:

Be it known that I, JOSEPH W. NETHERY, a citizen of the United States, residing at Indianapolis, in the county of Marion and State 5 of Indiana, have invented certain new and useful Improvements in Valves, of which the following is a specification.

My present invention relates to that class of valves which are adapted when opened to close 10 automatically and resembles in many particulars the similar valve which forms the subject-matter of my pending application, Serial No. 84,667, filed December 4, 1901. In valves of this class the movement of the 15 main valve results automatically from the pressure and flow of the water therethrough as soon as a release-valve has been operated by external pressure; and the primary object of my present invention is to provide a construction which shall be such that the operator cannot by a continuous pressure upon the release-valve cause a continuous flow of 20 water through the valve, the construction being such, on the contrary, that the principal flow of water through the valve can only take 25 place after the release-valve has been operated, released, and returned to its normal position.

A further object of my invention is to provide such improvements in details of construction as may hereinafter be pointed out.

The accompanying drawings illustrate my invention.

Figure 1 is a central vertical section with 35 the release-valve open and the main valve on its way upward. Fig. 2 is a similar view, the main valve, however, being shown in full and being shown in closed position and the release-valve being also shown in its closed position. Fig. 3 is a horizontal section on line 3 3 of Fig. 2. Fig. 4 is a similar view on line 4 4 in Fig. 2, and Fig. 5 is a vertical section on line 5 5 in Fig. 3.

My present invention is somewhat similar 45 in appearance to the valve shown in my pending application before mentioned, and the valve-casing consists of an outer shell 10 and an inner shell 11. The ingress-opening 12

leads into one side of the outer shell 10 and communication is had between the interior of the shell 10 and the interior of shell 11 through a comparatively narrow elongated slit 13, formed through the wall of shell 11 substantially opposite the ingress 12 and of an area substantially equal to or greater than the area of the ingress. 50 Slit 13 leads into shell 11 immediately above an annulus 19, which divides the interior of shell 11 into two chambers 14 and 14'. Formed at the lower end of shell 11 is a valve-seat 15, upon which normally rests a valve 16, carried 55 at the lower end of the main-valve body 17. The body 17 is provided with a pair of peripheral grooves 17' 17'', so as to thus form three portions *a*, *b*, and *c*, each of which is of a diameter substantially equal to the internal diameter of the annulus 19, the valve 16 being carried at the lower end of the portion *c*, while immediately above the portion *a* the main-valve body 17 carries a piston 18, which is of larger diameter than the main body 17 60 and fits in the piston-chamber 14. Piston 18 is hollow, as shown in Fig. 1, and mounted within the main body 17 is a buffer-pin 20, which is projected from the hollow portion of the piston 18 and is normally held so projected by a light 65 spring 21. Pin 20 has a possible retractive movement somewhat greater than the possible throw of the release-valve, to be described. 70

As in my previous valve, the upper ends of the two shells 10 and 11 are closed by a cap 80 30, which has formed in its interior a passage 32, communicating through a pair of converging passages 32' with a by-pass 33, leading downward between the two shells 10 and 11 and communicating with the egress-passage 85 34 below valve-seat 15. Projecting through cap 30 is the release-valve stem 36, which passes through a valve-seat 36', formed in the inner face of cap 30, and through a suitable packing-gland 36''. Valve-stem 36 carries at 90 its outer end a push-button 35 and at its inner end a release-valve 27, which seats on the seat 36', as in the construction already mentioned.

The passages 32' form a communication between the passage 32 in cap 30 and the by-pass 33, and in order to properly regulate the 95

flow which may take place through these bypasses 32' I provide a needle-valve 22, mounted in a suitable threaded opening, as is clearly shown in Fig. 5, which leads down between the bypasses 32' and communicates with the upper end of the passage 33 at the point of convergence of the two bypasses 32'. By this construction there is no danger of any leakage around the threads of the valve 22, resulting in a shifting of the valve 22, as in my former construction. Piston 18 divides the piston-chamber 14 into upper and lower portions X and Y, and communication is had therebetween by means of a small passage 26, the effective area of which may be effected by means of a small circular plate 28, held in any desired position with relation to the upper end of passage 26 by means of a screw 29.

In operation the normal positions of the parts are as shown in Fig. 2, portion *a* of the main-valve body extending into and fitting within annulus 19 and valve 16 resting upon seat 15, the lower end of the piston 18 lying somewhat above annulus 19, while release-valve 27 is seated against seat 36'. The normal pressure of water in the ingress 12 is exerted in the two portions X and Y of the chamber 14, the pressure within the chamber X serving to hold the main valve down and the release-valve up in closed position. The groove 17" is of less depth and of less width than groove 17' for a purpose which will appear. With the parts in the normal positions shown in Fig. 2 if the operator press down upon button 35 release-valve 27 will be forced downward away from seat 36' to such a distance that the suction of water, which thereupon passes through cap 30, around stem 36, into bypass 32, may not draw the release-valve upward, so as to close the same. As soon as a flow of water from chamber X through the bypass 32 is permitted by the depression of the release-valve 27 the pressure upon the upper end of piston 18 is removed, and the pressure in chamber Y, at the lower end of said piston, forces the piston upward through chamber 14, at the same time drawing the main-valve body 17 upward and withdrawing the portion *a* thereof from the annulus 19. As soon as this withdrawal takes place there is a slight flow of water through the annulus so long as groove 17" lies within the annulus; but this groove is of such width and depth that the available area of passage for outflow is considerably less than the area of ingress, so that there continues to be exerted upon the under side of piston 18 a pressure sufficient to continue the upward movement of the main-valve body 17. As the main-valve body continues to move upward the portion *b* is drawn through the annulus 19, and the outflow of water is temporarily discontinued until the groove 17' comes within the annulus, at which time a further outflow takes place; but groove 17', although deeper and wider than groove 17", is still of such di-

mensions that the available area for outflow through the annulus is less than the area of ingress, so that the main-valve body continues to move upward until the portion *c* comes into the annulus and again cuts off the flow of water through the annulus 19. Shortly before the upper end of the portion *c* comes into the annulus 19, so as to cut off the outflow of water through the annulus, the buffer-pin 20 engages valve 27 and moves the same upward until it seats against seat 36', the portion *c* of the main-valve body being at that time about to enter annulus 19. While this action has been taking place (the action, in fact, being quite rapid) the water which had been in chamber X has escaped freely around valve-stem 36 into passage 32 and from thence has escaped through passage 32' into passage 33 and through thence to the egress 34, the rate of flow through passages 32' being determined by the position of needle-valve 22 and this rate of flow determining the speed of upward movement of the main valve. As soon as the release-valve 27 has been seated on its seat 36' a preponderance of pressure upon the upper end of piston 18 is established through passage 26 and the main valve is moved downward by reason of such pressure, the release-valve remaining closed. Under normal conditions, therefore, portion *c* does not rise into annulus 19, the main valve starting on its return immediately before said part reaches the annulus. Suppose, however, that the operator, attempting to obtain a continuous flow of water, holds valve 27 down while the main valve is rising. In this case buffer-pin 20 prevents a sudden shock against the finger of the operator and also yields sufficiently to allow the main valve to proceed upwardly until portion *c* enters annulus 19 and completely shuts off the flow of water and remains in that position until the valve 27 is released by the operator and spring 21, through pin 20, has returned it to closed position, whereupon the main valve starts down, withdrawing portion *c* from the annulus and permitting a resumption of flow.

The possible yield of buffer-pin 20 is such that when the main valve is in the upper position and pin 20 has served to positively return valve 27 to closed position said pin may yield through a distance substantially equal to or greater than the possible opening throw of the release-valve less the length of that much of portion *c* as lies within the annulus. By this construction the operator may not after once releasing the pressure above the main valve, so as to allow it to rise from its seat, push button 35 downward enough to force the main valve down, so as to withdraw portion *c* from annulus 19. As a consequence, even though the operator maintain the release-valve away from its seat, there will be no outflow of water, and there will continue to be no outflow until the release-valve is al-

lowed to be returned in the manner already described and the main valve thereafter moved downward automatically by the accumulation of pressure in the chamber X until the portion c is withdrawn from the annulus and groove 17' brought into the annulus 19. Groove 17' is of such depth and width that during the time the main valve is moving downward through the width of said groove a sufficient quantity of water may pass through annulus 19 and valve-seat 15 to properly flush the closet to which the valve is intended to be attached. So soon as the main-valve body 17 has moved downward sufficiently to bring portion b into the annulus 19 said portion b serves to temporarily substantially totally discontinue the flow of water through the annulus, so that the flushing action of the closet is suspended, whereupon after the portion b has passed through the annulus a sufficient quantity of water may pass through the annulus when groove 17" is traveling therethrough to fill the basin of the closet without a flushing action. The continued downward movement of the main-valve body 17 brings the lower end of the portion a into annulus 19, and thus prevents further flow of water from the chamber Y through said annulus to the egress, and this action takes place when the valve 16 is still a short distance from the seat 15. As a consequence the body of water confined in the chamber Y serves as a check against the suction action of the water passing through the valve-seat 15 around the lower end c of the main-valve body, and the valve 16 drops slowly upon the seat 15 as the water confined in chamber Y escapes through the passage 26 into chamber X.

I claim as my invention—

1. The combination, in a valve structure, of the valve-casing, the main piston-valve therein the piston-head whereof divides the interior of the piston-chamber into upper and lower chambers and which is of larger area than the valve proper, means for supplying fluid slowly to the chamber above the piston-head; means for discharging the fluid from said chamber consisting of a by-pass leading therefrom and an auxiliary valve therein adapted to be opened from without and to be automatically closed by the main valve after it has moved from its initial seat, said main valve being fixedly connected with the piston-head whereby it is controlled by pressure on said piston-head, a valve-seat upon which said valve is adapted to rest when in closed position, a secondary shut-off structure with which a portion of the main valve may coöperate to substantially shut off the flow of fluid near the open position of the main valve, said secondary shut-off structure being located that distance from the normally closed position of the coöoperating portion of the valve substantially equal to the travel of said main valve

less the possible movement thereof by the auxiliary valve, whereby, when the automatically-closed auxiliary valve shall be held open and the main valve engaged thereby, the flow through the valve structure will be stopped, and when said auxiliary valve is released, the main valve will automatically close the auxiliary valve and thereafter return to the valve-seat, substantially as set forth. 65

2. In a valve structure of the class described, the combination with the main casing consisting of a pair of chambers separated by an annulus, of a main valve having a body fitting within said annulus and carrying a valve at its lower end, a valve-seat arranged at the discharge end of the lower chamber in position 75 for said valve to rest thereon, a piston-head of greater area than the main body carried thereby and fitting within the upper chamber, a by-pass leading from said upper chamber, a release-valve controlling said by-pass, and a 80 pair of separated peripheral grooves formed in the main body of the valve intermediate its ends whereby two distinct and separated flows of fluid are produced through the annulus during the automatic closing action of the main 85 valve. 90

3. In a valve structure of the class described, the combination of the main casing consisting of a pair of chambers separated by an annulus, 95 of a main valve having a body fitting within said annulus and carrying a valve at its lower end, a valve-seat arranged at the discharge end of said lower chamber in position for said valve to rest thereon, a piston-head of greater diameter than the main valve carried thereby 100 and fitting within the upper chamber, a by-pass leading from said upper chamber, a release-valve controlling said by-pass, and a buffer-pin carried by the main valve and yieldingly held into projected position, said buffer-pin 105 serving to engage the release-valve and return it to closed position when the main valve is automatically forced from its seat. 110

4. In a valve structure of the class described, the combination of the main casing consisting of a pair of chambers separated by an annulus, of a main valve having a body fitting within said annulus and carrying a valve at its lower end, a valve-seat arranged at the discharge end of the said lower chamber in position for said valve to rest thereon, a piston-head of greater diameter than the main valve carried thereby and fitting within the upper chamber, a by-pass leading from said upper chamber, a release-valve controlling said by-pass, a buffer-pin carried by the main valve and yieldingly held into projected position, said buffer-pin serving to engage the release-valve and return it to closed position when the main valve is automatically forced from its seat, and said buffer-pin having a possible movement within the main valve such that, 115 120 125

when the main valve is in its upper position, the release-valve cannot be operated so as to exert a displacing pressure upon the main valve, and means for cutting off the flow at 5 the limit of the upward travel of the main valve.

5. In a valve structure of the class described, the combination, with a main casing consisting of a pair of chambers separated by an annulus, of a main valve having a body passing through said annulus and carrying a valve at its lower end, a valve-seat arranged at the discharge end of the lower chamber in position to receive said valve, a piston-head of greater 10 diameter than the main valve carried thereby and fitting within the upper chamber, a by-pass leading from said upper chamber, a release-valve controlling said by-pass, a secondary shut-off structure carried by the body of 15 the main valve in position to fill the annulus when the main valve is in its upper position, and a yielding buffer-pin carried by said main valve and arranged to engage the release-valve and return it to closed position when the 20 main valve rises to open position, said buffer-pin having a possible movement relative to the main valve such that when the main valve is in its upper position an opening movement of the release-valve may not serve through 25 the buffer-pin to withdraw the secondary shut-off structure of the main valve from the annulus, for the purpose set forth.

6. In a valve structure of the class described, the combination, with the main casing, consisting of a pair of chambers separated by an annulus, of a main valve having a body fitting within said annulus and carrying a valve at its lower end, a valve-seat arranged at the discharge end of the lower chamber in position for 30 said valve to rest thereon, a piston-head of greater diameter than the main valve carried thereby and fitting within the upper chamber, a by-pass leading from said upper chamber, a release-valve controlling said by-pass, a pair 35 of separated peripheral grooves formed in the main body of the valve intermediate its ends whereby two distinct and separated flows of fluid are produced through the annulus during the automatic closing action of the main 40 valve, and a yielding buffer-pin carried by said main valve and arranged to engage the release-valve and return it to closed position when the main valve rises to open position, said buffer-pin having a possible movement 45 relative to the main valve such that when the main valve is in its upper position an opening movement of the release-valve may not serve through the buffer-pin to withdraw the secondary shut-off structure of the main valve 50 from the annulus, for the purpose set forth.

7. In a valve structure of the class described, the combination, with the main casing consisting of a pair of chambers separated by an annulus, of a main-valve body carrying a valve

at its lower end, a valve-seat arranged at the 65 discharge end of the lower chamber in position to receive said valve, a piston-head of greater diameter than the main-valve body carried thereby and fitting within the upper chamber, said piston having a greater effective area upon that face farthest from the valve, a by-pass leading from said upper chamber, a release-valve controlling said by-pass, a passage forming a restricted communication from one side of the piston to the other, and 70 a shut-off structure carried by the main-valve body immediately beneath the piston to enter the annulus before the main valve reaches its seat, whereby, before the main valve has reached its seat, the secondary shut-off structure will have entered the annulus and the piston will lie so close to said annulus as to form a cushion of fluid between itself and the annulus, for the purpose set forth.

8. In a valve structure of the class described, 85 the combination, with the main casing consisting of a pair of chambers separated by an annulus, of a main-valve body carrying a valve at its lower end, a valve-seat arranged at the discharge end of the lower chamber in position to receive said valve, a piston-head of greater 90 diameter than the main-valve body carried thereby and fitting within the upper chamber, a by-pass leading from said upper chamber, a release-valve controlling said by-pass, a passage forming a restricted communication from one side of the piston to the other, and a shut-off structure carried by the main-valve body immediately beneath the piston to enter the annulus before the main valve reaches its seat, whereby, before the main valve has reached its seat, the secondary shut-off structure will have entered the annulus and the piston will lie so close to said annulus that a quantity of fluid is momentarily caught between the annulus and the piston before the main valve reaches its seat, for the purpose set forth.

9. In a valve structure of the class described, the combination, with the main casing consisting of a pair of chambers separated by an annulus, of a main-valve body carrying a valve at its lower end, a valve-seat arranged at the discharge end of the lower chamber in position to receive said valve, a piston-head of 110 greater diameter than the main-valve body carried thereby and fitting within the upper chamber, said piston having a greater effective area upon the face farthest from the valve, a by-pass leading from said upper chamber, a release-valve controlling said by-pass, a passage forming a restricted communication from one side of the piston to the other, and a shut-off structure carried by the main-valve body immediately beneath the piston to enter 115 the annulus before the main valve reaches its seat, whereby, before the main valve has reached its seat, the secondary shut-off structure will have entered the annulus and the piston will lie so close to said annulus that a quantity of fluid is momentarily caught between the annulus and the piston before the main valve reaches its seat, for the purpose set forth.

120

125

ture will have entered the annulus and the piston will lie so close to said annulus that a quantity of fluid is momentarily caught between the annulus and the piston before the 5 main valve reaches its seat, for the purpose set forth.

In witness whereof I have hereunto set my

hand and seal, at Indianapolis, Indiana, this 7th day of October, A. D. 1902.
